(57) CLAIM

The ornamental design for a toilet paper storage cabinet and dispenser, as shown and described.

DESCRIPTION

FIG. 1 is a top, front, and right side perspective view of a first embodiment of a toilet paper storage cabinet and dispenser showing my new design;

FIG. 2 is a front elevation view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a top, front, and right side perspective view of a second embodiment of a toilet paper storage cabinet and dispenser showing my new design.

The broken-line disclosure of toilet paper rolls in the view is for illustrative purposes only and forms no part of the claimed design.
